United States Patent Office

Des. 175,794
Patented Oct. 11, 1955

175,794

SOCK

James Oliver, Atlantic City, N. J.

Application March 15, 1954, Serial No. 29,532

Term of patent 7 years

(Cl. D47—7)

The figure is a side elevation of the sock.

The other side of the sock is identical with the side shown.

I claim:

The ornamental design for a sock as shown and described.
